Primary Examiner — Sanjeev Paul(74) *Attorney, Agent, or Firm* — Thomas | Horstemeyer,
LLP(57) **CLAIM**

The ornamental design for spectacles, as shown and described.

DESCRIPTION

FIG. 1 is a perspective view of spectacles, showing our new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof; and,

FIG. 7 is a bottom view thereof.

The broken lines are for the purpose of representing environmental structure and form no part of the claimed design.

1 Claim, 7 Drawing Sheets(56)
